UNITED STATES PATENT OFFICE

153,005

DESIGN FOR A PAIR OF SPECTACLES OR
SIMILAR ARTICLE

Leslie W. Myers and Charles L. Waldo, Minneapolis, Minn., assignors to Cosmet Co., Minneapolis, Minn., a partnership

Application March 22, 1947, Serial No. 137,814

Term of patent 14 years

(CL. D57—1)

To all whom it may concern:

Be it known, that we, Leslie W. Myers and Charles L. Waldo, each of us citizens of the United States of America and residing in the city of Minneapolis, county of Hennepin, State of Minnesota, have invented a new, original, and ornamental Design for a Pair of Spectacles or Similar Article, of which the following is a specification, reference being made to the accompanying drawing, forming a part thereof, wherein:

Fig. 1 is a front elevational view of a pair of spectacles or similar article, showing our new design.

Fig. 2 is a top plan view of the same.

The essential features of our design for a pair of spectacles reside in the parts shown in full lines, particularly the arrangement of the outwardly protruding faceted elements on the lenses, all as illustrated.

We claim:

The ornamental design for a pair of spectacles or similar article, substantially as shown and described.

LESLIE W. MYERS.
CHARLES L. WALDO.
